UNITED STATES PATENT OFFICE.

PERLEY R. GLASS, OF QUINCY, MASSACHUSETTS, ASSIGNOR TO PEERLESS MACHINERY COMPANY, OF BOSTON, MASSACHUSETTS, A CORPORATION OF WEST VIRGINIA.

EYELETING-MACHINE.

SPECIFICATION forming part of Letters Patent No. 701,262, dated May 27, 1902.

Application filed April 6, 1901. Serial No. 54,657. (No model.)

To all whom it may concern:

Be it known that I, PERLEY R. GLASS, of Quincy, county of Norfolk, and State of Massachusetts, have invented an Improvement in Eyeletting-Machines, (Case A,) of which the following description, in connection with the accompanying drawings, is a specification, like letters on the drawings representing like parts.

10 The present invention relates to an eyeletting-machine, and is embodied in a machine for punching the holes for a number of eyelets and setting a number of eyelets at one operation.

15 The machine herein shown for the purpose of illustrating the invention is substantially like that shown in a prior United States patent granted to me May 7, 1901, No. 673,814, the invention relating mainly to improvements in the construction and arrangement 20 of the gages for the material, &c.

25 The invention further relates to novel means for forcing the material onto the punches after the material is perforated, so that the ends of the punches may protrude beyond the surface of the material to guide the eyelets, which are set or clenched by means of suitable setting devices coöperating with clenching-shoulders formed around 30 the punches.

35 It is usually desirable when eyelets are to be set in shoe-uppers to spread the eyelets—that is to say, to set them in a line which is not parallel with the edge of the upper—the eyelet nearest the toe portion standing farther away from the edge than the eyelet which is adjacent to the studs. In eyeleting the right and left members of an upper, therefore, it is necessary that the stock should be 40 gaged differently during the successive operations in order to obtain a proper spread, and one of the objects of this invention is to provide the machine with a gage which will be automatically shifted at the end of 45 each cycle of operations, so that the right and left members of an upper can be consecutively eyeleted on the same machine, the gage being in the right position for each of the said operations. The gage is arranged to extend 50 some distance along the edge of the up-

per, and is pivotally supported at a point substantially midway between the ends of the gangs of tools and arranged to be shifted on said pivotal support, so that first one end of the gage and then the other end will be moved laterally toward the said tools. The two positions of the gage are determined by stops, which may advantageously be adjustable, and the gage is connected with a traveling member of the machine, which is so arranged as to shift the gage at the end of each cycle of operations, the gage remaining stationary during the operation until after the eyelets have been clenched in the material and the tools have become separated therefrom. At the end of each cycle of operations, therefore, the gage is left in the proper position to coöperate with the other member of the upper without care or attention on the part of the operator.

70 The machine is further provided with gages to determine the endwise position of the upper, there being two such gages—one for each member of the upper—the position of which upper of course has to be shifted between the 75 operations on the two members thereof. These gages are adjustable, so as to be accommodated to uppers of different sizes or styles, and in order that the adjustment may be readily effected and may be uniform in 80 all cases the gages are provided with a common adjusting device which coöperates with both, so that the two end gages always bear the same relation to the edge gage, thus insuring uniformity in the eyeleting of the two 85 members of the upper.

A further feature of the invention consists in an end gage of novel construction, the said gage consisting of a member adapted to coöperate with one of the lacing-studs in 90 cases where the lacing-studs have been previously set, this insuring the proper relation between the studs and the eyelets on both members of the upper.

95 The machine embodying the invention is shown as provided with a set of tools each of which has a tubular punching portion and an annular clenching portion, the punching portion first coöperating with an anvil to perforate the material, and the clenching portion 100

then coöoperating with other setting devices which are provided with means for taking up the eyelets to carry them toward the material.

- 5 In order that the material may remain in engagement with the punches after the holes have been made, and also that the said punches may project beyond the surface of the material to guide the eyelets into the 10 holes, the machine is provided with novel means for forcing the material toward the clenching portions of the punches as soon as the holes are made, the anvil-carrier being provided with an engaging member yieldingly 15 supported in such a position as to project above the anvil, the said member having openings to permit the punches to coöperate with the anvil. The said member has sufficient bearing-surface to support the material 20 when the punches come in contact therewith, and will yield as the punches and anvils come together until the punches have actually perforated the material, leaving the said material free to move with relation to the 25 punches, the yielding member then forcing the material on the punches as is desired.

Figure 1 is a side elevation of a machine embodying the invention. Fig. 2 is a partial top plan view of the same, illustrating the 30 construction of the gage-operating mechanism. Fig. 3 is a partial top plan view showing the end gages adapted to coact with previously-inserted lacing-studs; and Figs. 4, 5, and 6 details on an enlarged scale showing 35 the means for forcing the material toward the clenching portions of the punches after the punching operation is completed.

- Referring to Fig. 1, the machine is shown as provided with a gang of punches *a*, mounted 40 in an overhanging arm or projection *A*², which forms part of the frame *A*, the said punches being directly over a supporting-table *A*³, which is provided with an opening for a vertically-reciprocating anvil member *b* 45 and a gang of vertically-reciprocating setting devices *c*, which are provided with yielding fingers *c*² to pick up the eyelets from suitable raceways formed in a feed-chute *D* in the ordinary way. In the operation of the machine the anvil member *b* first rises, carrying 50 the material up into engagement with the tubular cutting portions of the punches *a* to perform the punching operation, then receding and leaving the material on the said tubular cutting portions and moving laterally in its downward movement, so as not to interfere with the subsequent upward movement of the setting devices *c*, which complete the eyeleting operation.
- 60 In order properly to spread the eyelets, the table *A*³ is provided with a gage *d*, which is shown as pivotally supported at *d*², the point of pivotal support being substantially midway between the ends of the gangs of tools, 65 the said gage being adapted to swing on said support between adjustable stops *e*, which

are adapted to limit the said swinging movement.

The gage *d* is sufficiently long to lie in contact with the material for some distance along 70 the edge thereof, and as it swings on its pivot with relation to the gangs of tools it will cause the said edge of the material to stand at an angle to the gangs of tools, the apex of said angle being at one end or the other in accordance 75 with the position of the said gage, so as to spread the eyelets along either member of the upper, one position being necessary for one member and the other position necessary for the other member, since the position of 80 the upper must be reversed between successive operations in order to set eyelets in both members consecutively.

To produce the shifting of the gage *d* automatically, the said gage is herein shown as 85 connected by means of a link *d*³ with an elbow-lever *d*⁴, pivotally connected with the frame *A*, one member of said elbow-lever being operated upon by a reciprocating arm *d*⁵, which is arranged to move in one direction at 90 the end of a cycle of operations and in the other direction at the end of the next cycle of operations. As herein shown, the said arm *d*⁵ is acted upon by a cam-groove *d*⁷, which receives a cam-roll *d*⁶ at the end of the said 95 arm, and the said cam-groove is shown as formed in a rotating disk *d*⁸, mounted on a counter-shaft *d*⁹ and provided with gear-teeth *d*¹⁰, the said teeth intermeshing with the teeth of a gear *B*² on the main shaft *B* in the ratio 100 of two to one, the said cam-groove thus making only one-half a revolution to each one revolution of the main shaft.

The cam-groove *d*⁷, as shown in Fig. 1, is of such shape as to produce a movement of the 105 arm *d*⁵ during the last part of the rotation of the main shaft *B*, such movement therefore taking place after the setting devices *c* have receded far enough to release the material, so that the gage *d* is free to move. This 110 leaves the gage standing in the other position ready for the other member of the upper, the shape of the cam-groove being such as to produce no movement of the gage until the next eyeleting operation has been completed. 115

In order to compensate for the various adjustments, the elbow-lever *d*⁴ is yieldingly connected with the arm *d*⁵, as by springs *d*¹¹, the said springs acting both ways to seat the gage *d* against one or the other of the stops *e* 120 regardless of the position of the said stops, it being unnecessary, therefore, to vary the extent of movement of the arm *d*⁵ if the positions of the stops *e* are varied or the gage *d* as a whole adjusted with relation to the gangs 125 of tools, as by the adjustable connections *A*⁴ of the table *A*³.

In order to gage the endwise position of uppers in which lacing-studs have previously been set, the machine may be provided in 130 accordance with the invention with end gages which consist of members *f*, mounted in the

table, so as to engage one of the lacing-studs, as indicated in dotted lines, Fig. 3, the upper being inverted during the eyeleting operation, so that the studs project downward. 5 The machine is provided with two of such gages, one for each member of the upper, and in order that these gages may be easily adjusted for use with different sizes or styles of uppers and also that a symmetrical adjustment may be secured, so that both members of the upper will be gaged alike, the gages are provided with a common adjusting device adapted to operate equally on both.

As shown in Fig. 3, each gage f is provided 15 with a slide or carrier f^2 , the said carriers being provided with rack-teeth f^3 , both of which sets of rack-teeth are adapted to be acted upon by a pinion f^4 , provided with an actuating member or handle f^5 . The said 20 rack-teeth f^3 are arranged on opposite sides of the said pinion f^4 so that the rotation thereof in either direction will produce movements of both gages f corresponding to each other, but in opposite directions, so that 25 both gages at once will be moved equal distances toward or from the gangs of tools, as is necessary for the proper gaging of each upper during each of the successive operations thereon.

30 The handle f^5 may be arranged to travel along a scale member f^6 , provided with retaining-notches f^7 , the distance between which may be arranged to accommodate any degree of adjustment required. A similar 35 common adjusting device may be applied to end gages adapted to coöperate with the top edge of the upper in case the eyelets are set before the uppers have been provided with lacing-studs. Such a construction is shown 40 in Figs. 1 and 2, in which the end gages f^{10} , which are arranged at the corners of the table A^8 , are mounted in guides and provided 45 with rack-teeth f^{30} , intermeshing with pinions f^{40} , each pinion having connected therewith a crank or radial projection f^{41} , which cranks are connected together by means of a link f^{42} , so that if one of the pinions is moved a corresponding movement is imparted to the other.

50 As shown in Fig. 2, one of the pinions may be provided with a handle f^{50} , movable along a suitable scale member f^{60} , and provided with retaining-notches f^{70} . While this form of actuator is simple and convenient of operation, 55 it is obvious that any other suitable form of actuator may be employed, while the connection between the gages may be modified, the object of the invention being to provide the gages f^{10} with means for equal adjustment, 60 so that the difficulty of getting both gages adjusted in such a way as to get the same results with the two members of an upper is obviated.

The means for forcing the material up onto 65 the punches a after the holes are made are illustrated in Figs. 4, 5, and 6, the anvil member b being shown as provided with a set of

anvils b^2 , one for each punch a , the said anvils projecting upward from the surface of the said anvil member. The said anvil member is further provided with a yielding support b^3 , which normally stands, as shown, above the said anvil member and is provided with openings b^4 , which are sufficiently large to surround the anvils b^2 , so as to permit the depression of the said support b^3 to a point substantially level with the surfaces of the anvils. The said support is held in its normal position by means of springs b^5 , which are of such strength that they will yield when the material engages the punches a in the upward movement of the anvil member, so that the anvils b^2 are forced upward against the material interposed between them and the punches until the anvils and punches come 85 together to completely perforate the material, which is then free to move upward along the punches, as indicated in Fig. 5. The springs are, however, sufficiently strong to overcome the resistance afforded by the tapered outer surfaces of the punch, so that as soon as the material is actually perforated it will be forced upward onto the punches, remaining there with the punches protruding and ready to receive the eyelets from the 95 clenching devices c when they move upward after the anvil member has traveled out of the way.

The yielding support b^3 may be secured in the anvil member b in any suitable or usual 100 way, being herein shown as provided with supporting-rods b^6 , extending through vertical openings in the anvil member b and provided with heads b^7 to maintain the support b^3 in its proper normal position. The springs 105 b^5 are shown as spiral springs held in position by means of pins b^8 , extending through suitable openings in the anvil member b and affording additional guides for the support b^3 , 110 as well as retaining members for the springs which are interposed between the lower surface of said support and the upper surface of the member b .

I claim—

1. In an eyeleting-machine provided with a 115 gang of punches and a gang of setting devices, a gage adjacent to the punches and setting devices, and having an elongated gaging portion to extend some distance along the edge of the material, said gage being movable 120 around an axis midway between the ends of the gangs of tools; and means for automatically moving said gage on said axis after each setting operation, as set forth.

2. In an eyeleting-machine provided with a 125 gang of punches, an edge gage for the material pivotally supported at a point midway between the ends of said gang of punches; stops to limit the pivotal movement thereof; an operating member connected with said 130 gage; and means for moving said member in one direction at the end of one cycle of operations, and in the other direction at the end of the next cycle of operations, as set forth.

3. In an eyeleting-machine of the class described, the pivotally-supported edge gage for the material; an operating-rod connected with said gage to produce a movement thereof on its pivot; a cam coöperating with said rod arranged to produce a movement thereof in one direction substantially at the end of half a revolution of said cam, and a movement thereof in the other direction substantially at the end of the other half-revolution; and means for connecting the said cam with the operating-shaft of the machine to cause the said cam to make one revolution at each two revolutions of said shaft, as set forth.
- 15 4. In an eyeleting-machine of the class described, a gage for the edge of the material pivotally supported; a reciprocating operating member for moving the said gage on its pivot; adjustable stops to limit the pivotal movement of said gage in either direction; and a yielding connection between the said gage and the said reciprocating operating member, as set forth.
5. In a machine for eyeleting shoe-uppers in which lacing-studs have been previously inserted, the combination with means for punching a plurality of holes in the material and setting a plurality of eyelets therein by a single cycle of operations; of a gage for the material so positioned as to coöperate with a previously-inserted lacing-stud, substantially as described.
- 25 6. In an eyeleting-machine for consecutively setting a gang of eyelets in the right and left members of a shoe-upper, an end gage for each of said members; and an adjusting device for the said end gages which is common to both, as set forth.
- 30 7. In an eyeleting-machine for consecutively setting eyelets in the two members of an upper previously supplied with lacing-hooks, a gage for each member of the upper below the support for the material to coöperate with one of the lacing-studs; an adjusting-pinion; and a rack connected with each gage, the said racks intermeshing with opposite sides of the said pinion whereby the said gages may be equally adjusted in opposite directions at one operation, as set forth.
- 35 8. In an eyeleting-machine, the combination with a tubular punch provided with an annular clenching-surface; of an anvil to coöperate with the said punch in perforating the material; means for bringing the said punch and anvil together; a spring-support for the material normally projecting above the said anvil and having an opening for the punch and anvil, the strength of the springs for said support being sufficient to force the material onto the punch after the material is perforated, substantially as described.
- 40 In testimony whereof I have signed my name to this specification in the presence of two subscribing witnesses.
